ELECTRICAL PROTECTIVE DEVICE

George F. Lincks, Pittsfield, Mass., assignor to
General Electric Company, a corporation of
New York

Application September 20, 1949, Serial No. 116,701

3 Claims. (Cl. 175—294)

1

My invention relates to electrical protective devices of the fuseless cutout type which are frequently employed to isolate faulted lines in electric distribution systems. More particularly, my invention relates to a type of fuseless cutout which imposes a metallic short circuit upon a faulted line to cause an associated circuit interrupting device to interrupt the fault prior to isolation thereof by the fuseless cutout.

In my copending application Serial No. 116,702, filed September 20, 1949 and assigned to the same assignee as the present invention, I disclose a type of fuseless cutout in which an arc-suppressing device such as an arc chute is provided to aid in extinguishing an arc which forms in the switching element of a cutout when the latter opens in response to a fault condition. Should such an arc fail to be extinguished by arc-suppressing action in the cutout, the arc is transferred from the faulted line to an auxiliary arcing electrode preferably located in the arc chute and connected to ground or another suitable return path. Following transfer of the arc, arc-suppressing action in the cutout continues to aid in extinguishment of the arc.

The effect of transferring the arc is to short-circuit the line through the arc. Such short-circuiting action results generally, in case the arc is not extinguished by arc-suppressing action in the cutout, in the opening of an associated circuit breaker which interrupts the line and extinguishes the arc. A principal feature of the device disclosed in the above-mentioned copending application is, therefore, to effect, whenever possible, interruption of a faulted line by action of the cutout itself, rather than by opening of a main reclosing circuit breaker, to reduce to a minimum the number of momentary outages occurring in branch circuits in which faults do not exist.

In many cases, it is desirable to effect interruption of a faulted line by action of a cutout itself in the manner described. In certain applications, however, a cutout of the type mentioned, even with properly designed arc chutes, may not be depended upon to interrupt a major portion of faults without actually causing a short circuit across the line through the transferred arc and requiring the reclosing circuit breaker to interrupt the arcing current. Therefore, in applications of the latter type, it is frequently desirable to impose a definite short circuit on a line to force operation of the circuit breaker, rather than attempt to clear the fault at the cutout.

While the use of an arc as a short-circuiting device is now directed to the following descrip-

medium is satisfactory in some cases, in many applications the presence of a flaming arc, particularly of the magnitude resulting from a low-impedance short circuit, is objectionable or dangerous. It is desirable, therefore, to provide in a fuseless cutout wherein a definite short circuit is desired a short-circuiting arrangement through metallic contact or other means to prevent formation of an arc.

An additional advantage of short-circuiting a line in response to a fault to cause operation of a circuit breaking device is that the predetermined current causing operation of a cutout device may be made appreciably lower and protection may be provided for a relatively greater length of line than would otherwise be the case. If a short-circuiting action is not provided, the current required to cause opening of the cutout must be at least equal to the minimum operating current of the reclosing circuit breaker to assure operation of the breaker. Otherwise, circuit-interrupting requirements for which the cutout is not designed may be imposed thereupon.

It is the principal object of my invention to provide a new and improved fuseless cutout to short-circuit a line through a suitable return path in response to a fault condition and to isolate the faulted line following interruption of the short-circuit by an associated circuit breaking device.

In accordance with a preferred embodiment of my invention, I provide a fuseless cutout of the open type in which a current-responsive element such as a thermostatic device effects closing of a switching mechanism in response to a fault condition beyond the cutout to short-circuit the faulted line through a suitable return path such as ground. Following the short-circuiting operation, an associated circuit breaking device is caused to open, thereby interrupting the fault. A second current-responsive element, preferably an electromagnetic device, is arranged to prevent opening of the main switch mechanism of the cutout initially in response to the fault, but to release and cause opening of the main switch mechanism and isolation of the faulted line following interruption of the short-circuit current by the circuit breaking device. According to another preferred embodiment, I provide an enclosed cutout device in which a single current-responsive element, preferably an electromagnetic device, is arranged to effect in sequence the short-circuiting and circuit opening functions previously described.

For a better understanding of my invention, attention is now directed to the following descrip-

tion taken in connection with the accompanying drawings and to the appended claims, in which the features of my invention believed to be novel are more particularly set forth. In the drawings, Fig. 1 is a side elevational view of an open cutout device embodying certain features of my invention; Figs. 1a and 1b are end views of certain elements shown in Fig. 1; Fig. 2 is a front elevational view of the device shown in Fig. 1; Fig. 4 is a side elevational view, partially sectionalized, of an enclosed cutout device embodying certain features of my invention; and Figs. 3 and 5 are schematic diagrams showing the electrical relationship of certain elements of the devices shown in Figs. 1 and 4, respectively.

Referring now to Figs. 1, 1a, 1b and 2, there is shown a fuseless cutout of the open type for use in a line of an electrical distribution system. Cutout 1 is provided with an insulating member 2 on which are mounted an incoming or line terminal 3 and an outgoing or load terminal 4. Insulator 2, which is preferably formed of an inorganic material, such as porcelain or glass, may be of conventional design and is of a size suitable for the line voltage with which cutout 1 is to be employed. Insulator 2, which forms the principal supporting member for the elements of cutout 1, is provided with a hanger 5 which is employed in mounting cutout 1 to an external supporting structure (not shown). Hanger 5 is a metallic strap clamped about the approximate center of insulator 2 by a screw 6 and nut 7. Hanger 5 also serves as an auxiliary terminal for cutout 1 to which suitable return path is connected, as will hereinafter be described.

Terminal 3 is a threaded lug fastened as by cementing in the upper end of insulator 2, while terminal 4 is a threaded lug similarly fastened in the lower end of insulator 2. A pair of switch mechanisms provided for cutout 1 may be conveniently designated as a main switching mechanism 8 and an auxiliary switching mechanism 9. Main switching mechanism 8 comprises principally a contact 10, a switch arm 11 and a flipper arm 12.

Contact 10 and flipper arm 12, which are shown in detail in Figs. 1a and 1b, respectively, may conveniently be formed of a wire having a relatively high degree of elasticity. Contact 10, which is generally symmetrical about its center line, may be formed from a single length of wire doubled to provide a mounting loop 13 at one end of contact 10 for securing to lug 3 by the use of a pair of suitable washers 14 and a nut 15. The opposite portions of wire leading from loop 13 are brought together and secured by brazing or otherwise to form a straight portion 16 at the approximate center of contact 10.

The free end of contact 10 is provided with an eyelet portion 17 arranged to engage arm 11, and a pair of catch portions 18 arranged to engage an auxiliary switch arm, as will be described. Eyelet 17 is formed by providing a pair of outwardly projecting half-loops in the wire forming contact 10. Since the opposite portions of contact 10 are secured together at center portion 16 and contact 10 is formed of a spring material, eyelet 17 is normally maintained in a substantially closed position. However, opposite sides of eyelet 17 at the end thereof away from center portion 16 may be spread apart by opposing the spring action tending to hold eyelet 17 closed, as by forcing switch arm 11 into engagement with contact 10 in eyelet 17. Catch portions 18 are formed in contact 10 by providing downwardly

projecting half-loops in the ends of the wire forming contact 10.

Flipper arm 12 may conveniently be formed of a single length of wire doubled to provide a mounting loop 19 for securing flipper arm 12 in fixed relation to insulator 2 at lug 4. Flipper arm 12 is electrically insulated from lug 4 by an insulating spacer 20 and an insulating washer 20'. Washer 20', loop 19, spacer 20 and a supporting member 21, to be described hereinafter, are clamped to insulator 2 by the use of a nut 22 threadedly engaged with lug 4. Flipper arm 12 is symmetrical about its center line and is provided with one or more spring loops 23 wound therein in the vicinity of loop 19. The lengths of wire extending from loops 23 are joined by brazing or otherwise to form a straight portion 24 which extends approximately one-half of the length of flipper arm 12. A pair of bands 24' provide additional fastening action at the ends of straight portion 24.

Beyond the end of straight portion 24, the free ends of the doubled wire forming arm 12 are formed into a pair of loops 24'' spaced apart sufficiently to receive therebetween a similar loop 25 formed in the lower end of switch arm 11. In other words, flipper arm 12 and switch arm 11 are joined in a hinged relation by interlocking loops 24'' and 25 with a screw 26 and nut 27. A biasing spring 28 is attached to arms 11 and 12 at the junction thereof. Spring 28 has a tendency to bias arm 11 in a clockwise direction with respect to arm 12. Spring loops 23 have a tendency to bias switch arm 12 in a clockwise direction about the center of loops 23.

A pair of latch mechanisms 29 and 30 are provided to maintain flipper arm 12 and switch arm 11 in predetermined positions. Latch mechanisms 29 and 30 are supported at the free end of supporting member 21, which may conveniently take the form of a rigid plate of an insulating material. Latch mechanism 29 comprises a current-responsive element, preferably a bimetallic device 31, and a latch 32. Latch mechanism 30 comprises a second current-responsive element, preferably an electromagnetic device 33, and a second latch 34.

Latches 32 and 34 are supported by a common supporting member 35 which is represented as a generally U-shaped member fastened to support 21 by one or more screws 36. Latches 32 and 34 are supported by a pair of pins 37 loosely fitted to permit latches 32 and 34 to pivot freely thereabout. Support 35 is positioned so as to be substantially in a plane with straight portion 24 of flipper arm 12. Thus, as arm 12 is rotated in a counterclockwise direction against the biasing action of spring loops 23, straight portion 24 may be positioned within support 35 where engagement is made between straight portion 24 and latches 32 and 34. The inside width of support 35 and the projection of latches 32 and 34 in support 35 are so arranged that arm 12 may be maintained in a latched position by either latch 32 or 34, provided the latches are maintained in latching positions through external forces acting thereupon. It will be noted that latch 34 is longer than latch 32. Thus, flipper arm 12 is maintained in a higher or more counterclockwise position by latch 32 than by latch 34.

Thermostatic element 31 and electromagnetic element 33 are employed to control the latching actions of latches 32 and 34, respectively. Thermostatic element 31 comprises a mounting bracket 38 fastened to support 21 by one or more

screws 39. A pair of bimetallic strips 40 and 41 are fastened to a block 42 of insulating material which, in turn, is secured to support 38 by one or more suitable screws 43. Strips 40 and 41 are insulated from each other at the upper ends thereof but are electrically joined by a generally U-shaped bracket 44, secured to the lower end thereof by brazing or otherwise. A screw 45, having an insulating head 46, is threadedly engaged with bracket 44.

Head 46 is arranged to engage latch 32. At relatively low temperatures, such as normal atmospheric temperatures, bimetallic strips 40 and 41 are in a generally flat condition and screw 45 is adapted to maintain latch 32 in its latched position. Heating of bimetallic strips 40 and 41 causes bending thereof in a clockwise direction about support 42. As such bending occurs, screw head 46 is caused to move away from latch 32, leaving latch 32 free to pivot outwardly with respect to support 35, thereby releasing straight portion 24 of arm 12 from further latching action by latch 32.

Electromagnetic device 33 may be of conventional solenoid design and is shown as comprising principally a plunger or armature 47, a frame 48 and a winding 49. Plunger 47 and frame 48 are formed of a magnetic material, such as iron. Electromagnetic device 33 is mounted and adjusted in such a manner that when a relatively high current flows through winding 49, creating a substantial magnetic field in device 33, armature or plunger 47 is caused to engage latch 34 and maintain it in its latching position. However, should the current through winding 49 be interrupted, thereby reducing the magnetic field to a negligible value, then plunger 47 ceases to exert a force on latch 34, which is then free to move away from its latching position to permit flipper arm 12 to be unlatched.

The sequence of latching and unlatching of flipper arm 12 is as follows: When arm 12 is in its free position, it is biased by spring loop 23 to a clockwise position shown in Fig. 1 by a broken-line view 12' of arm 12. As arm 12 is rotated in a counterclockwise direction by an operator, straight portion 24 enters support 35 at the opening thereof where it may be guided by an angularly disposed extremity 50 of support 35. Engagement is first made with the lower or cam-like surface of latch 34, which causes latch 34 to be forced outwardly to permit straight portion 24 to pass thereby. Similarly, as straight portion 24 engages the lower or cam-like surface of latch 32, latch 32 is forced outwardly against the spring action of bimetallic strips 40 and 41 to permit straight portion 24 to pass by latch 32. Thereafter, the spring action mentioned forces latch 32 inwardly with respect to support 35, thereby effectively maintaining flipper arm 12 in its latched position, as shown in Figs. 1 and 2. If latch 32 is now released, arm 12 is biased downwardly and if no force is exerted by plunger 47 on latch 34, arm 12 is free to return to unlatched position. However, if a force is exerted inwardly on latch 34, arm 12 is engaged thereby, following release by latch 32, and arm 12 is maintained in a lower latched position, indicated in Fig. 1 by a broken-line view 12''. The significance of having two latched positions of flipper arm 12 in addition to a free position thereof will become more apparent as the operation of switching mechanisms 8 and 9 is described.

Attention is next directed to the structure of auxiliary switching mechanism 9, which com-

prises principally a contact 51, a switch arm 52 and a restraining arm 53. Contact 51 is formed of a short length of wire secured by a screw 54 to hanger 5. Contact 51 is mounted in the principal plane of cutout 1 and is normal thereto. Switch arm 52 is supported by an insulating member 55 secured in fixed relation to switch arm 11 by clamping or otherwise. Arm 52 is pivotally mounted in support 55 and is arranged to pivot with respect to arm 11.

The motion and positions of arm 52 are closely associated with the latched positions of arm 12 and will be considered with respect thereto. It is first assumed that arm 12 is in its upper latched or normal operating position, and that arm 11 is engaged with eyelet 17 of contact 10, as shown in Fig. 1. Under this condition, arm 52 does not engage contact 51, but is maintained in an open position by engagement of restraining arm 53 with catch portion 18 of contact 10. Restraining arm 53 and switch arm 52 may conveniently be formed of a single piece of wire or rod suitably bent to form switch arm 52, a bearing portion 56 mounted in insulator 55, restraining arm 53, and an engaging portion 53' formed at the end of arm 53 and arranged to engage catch 18. A bias spring 57 is provided between arm 52 and support 55, tending to rotate arms 52 and 53 in a clockwise direction with respect to arm 11.

If latch 32 is released, permitting flipper arm 12 to move to its lower latched position 12'' and be maintained therat by latch 34, then arm 11 is dropped to a lower position and engaging portion 53' of restraining arm 53 no longer engages catch 18. In other words, under this condition arm 52 is free to pivot and is biased in a clockwise direction into engagement with contact 51 by action of spring 57. The length of arm 11 is such that upper extremity 58 thereof is maintained in engagement with contact 10 in the lower latched position of arm 12. However, upon release of latch 34, flipper arm 12 is permitted to move to its free position 12', thereby causing arm 11 to be freed from engagement with contact 10 and to drop away therefrom. The motion of arm 11 is further aided by biasing spring 28. As arm 11 is caused to drop, arm 52 is likewise disengaged from contact 51 and under this condition switch mechanisms 8 and 9 are both effectively opened.

To provide the desired conducting paths through cutout device 1, a lead 59 is connected from terminal 4, through the use of a suitable conducting washer 60 interposed between support 21 and insulator 2, to the upper end of bimetallic strip 40. A second lead 61 is connected between the upper end of bimetallic strip 41 and one end of winding 49, which also is connected by the use of a flexible lead 62 to switch arm 52. The other end of winding 49 is connected to flipper arm 12.

Two principal conducting paths are provided through cutout 1. The first or normal path is from terminal 3 through contact 10, switch arm 11, flipper arm 12, magnetic winding 49, lead 61, bimetallic strips 41 and 40, and lead 59 to terminal 4. A second or short-circuiting path exists following release of arm 52 and engagement thereof with contact 51. The second path is from terminal 3 through contact 10, switch arm 11, flipper arm 12, magnetic winding 49, flexible lead 62, switch arm 52, and contact 51 to auxiliary terminal 5.

The electrical relationship of elements mentioned and the conducting paths therethrough are shown schematically in Fig. 3, in which cut-

out 1 is shown within a closed broken line. Main switching mechanism 8 is shown in a closed position in Fig. 3, while auxiliary switching mechanism 9 is shown in an open position. Switches 8 and 9 are shown, therefore, in their normal operating positions, indicating the normal conducting path through device 1 from terminal 3 to terminal 4. Following release of flipper arm 12 to its lower latched position, switch 9 is closed by release of arm 52 and conducting paths exist through device 1 from terminal 3 to terminal 4 and from terminal 3 to terminal 5.

In the operation of the device described, it is assumed that cutout device 1 is inserted in a line in an electrical distribution system in combination with a reclosing circuit interrupter which is not shown. The incoming line is connected to terminal 3. The outgoing or load line is connected to terminal 4 and terminal 5 is connected to a suitable return path, such as ground. For normal operation, flipper arm 12 is placed in its upper latched position. Arm 11 is placed in engagement with contact 10 in eyelet 17 and restraining portion 53' of arm 52 is placed in engagement with catch 18. Thus, the normal load current flows through switch 8 and through thermostatic element 31.

If a fault condition occurs beyond device 1 causing an abnormal current to flow through thermostatic element 31, abnormal heating occurs therein. Under this condition, bimetallic strips 40 and 41 bend outwardly, releasing latch 32 and causing flipper arm 12 to drop to its lower latched position 12''. The fault current through winding 49 causes plunger 47 to lock latch 34 to maintain flipper arm 12 in its lower latched position 12''. Arm 11 is likewise dropped by an amount sufficient to release arm 52 from catch 18, permitting arm 52 to be biased into engagement with contact 51 by spring 57. Under this condition, a low-impedance short-circuit is created between terminals 3 and 5 or between the line and ground. The short-circuit current flows through switch 8, winding 49 of solenoid 33, flexible lead 62 and switch 9. As long as this relatively high current continues to flow through winding 49, it causes plunger 47 to continue to lock latch 34 to maintain flipper arm 12 in its lower latched position 12''.

Following the short-circuiting of the incoming line and the establishment of a relatively high short-circuit current, the external circuit interrupter is caused to open, thereby interrupting the current through device 1 and particularly through winding 49. Plunger 47, therefore, no longer exerts a force on latch 34 and flipper arm 12 is released, thereby to be biased to its free position 12' by spring loops 23. As arm 12 moves to its free position, arm 11 is disengaged from contact 10 and moving clockwise under bias of spring 28 disengages arm 52 from contact 51, removing the short-circuit. Also, the faulted line is isolated from the distribution system and the reclosing circuit interrupter may re-establish service on the remainder of the distribution system. Following the sequence of operation described, cutout 1 is in open position and may be reclosed by an operator, as previously described, following removal of the fault condition in the outgoing line.

By the use of a cutout device constructed in accordance with my invention, it is possible to impose a positive metallic short circuit on a line in response to a fault condition therein without an accompanying flaming arc. Another feature of

my invention, as herein embodied, is the isolation of the faulted line from ground following opening of the cutout. Such isolation of the faulted line is highly desirable since, in many distribution systems in common use, grounding of a faulted line may cause undesired grounding of other points in the system following restoration of service by reclosing action of the circuit interrupter.

Referring now to Fig. 4, there is shown, partially sectioned, a fuseless cutout 75 of the enclosed type embodying certain features of my invention. Cutout 75 is provided with a housing 76, preferably formed of an inorganic material such as porcelain. Housing 76 forms the principal supporting member for the elements of device 75 and is arranged to form the top, back and side surfaces of the cutout. Cutout 75 is supported on an external supporting structure (not shown) by a hanger 77 fastened to a back surface of housing 76 by cementing or otherwise.

The operating elements of cutout 1 are for the most part supported on a door member 78, formed of an insulating material such as molded compound. The operating elements and door member 78 form a door assembly 79 which is hinged with respect to housing 76 at a pivot 80, which may be a pin fixed to a bracket 81, the latter being fastened as by cementing in the lower portion of housing 76. Door assembly 79 comprises principally, in addition to door member 78, a metallic supporting member 82, an electromagnetic device 83, a slidable rod 84, a toggle member 85, and a mounting bracket 86. Supporting member 82 is secured in fixed relation to door 78 by the use of a plurality of threaded studs 87 fastened as by inserts molded in member 78, and a plurality of nuts 88.

Bracket 86 is secured in fixed relation as by welding to supporting member 82. One function of bracket 86 is to form a support for slidable rod 84. Rod 84 and an insulative sleeve 89 are concentrically positioned in a tubular portion 86' of bracket 86. Sleeve 89 may be a relatively tight fit in tubular portion 86' of bracket 86, but rod 84 is slidably supported in sleeve 89. Sleeve 89 is provided with a lip portion 90 at the upper end thereof to secure a definite position of sleeve 89 with respect to bracket 86.

Electromagnetic element 83 comprises a frame member 91 formed of magnetic material, such as iron, and a winding 92 wound thereon. Frame 91 is secured in fixed relation, as by welding, to bracket 86 or support 82, whichever is more convenient. Toggle member 85 is pivotally mounted with respect to bracket 86 by the use of a pin 93 and is insulated from bracket 86 by the use of an insulating sleeve 94. Toggle member 85 is provided with a hook portion 95 which, in combination with pin 80, serves as a hinge for door assembly 79. Toggle member 85 extends beyond pivot point 93 in the vicinity of electromagnetic element 83 and this portion of member 85 is formed of a magnetic material, such as iron, so that it constitutes an armature responsive to magnetic forces established in magnetic element 83.

It will be seen from the description thus far that the elements mentioned as forming door assembly 79 are mounted on support 78 and the entire assembly is arranged to pivot about pin 80 and be supported thereby through hook 95. A latch element 96 is provided at the free extremity of bracket 86 and is arranged to engage a catch element 97 fixed as by cementing in housing 76. The cooperating combination of

latch 96 and catch 97 serves two principal functions. The first is to form the elements of a main switch mechanism of cutout 75, and the second is to serve as a latch to maintain door assembly 79 in a closed position.

Catch 97 serves as an incoming or line terminal for cutout 75. In normal operation, latch 96 is arranged to be maintained in latching engagement with catch 97 to permit conduction of current therebetween and to maintain door assembly 79 in closed position. An outgoing or load terminal for cutout 75 is provided by a lug 98 formed of a conducting material and secured in fixed relation with respect to housing 76 by the use of a threaded stud 99 cemented therein and a nut 100. Lug 98 is arranged to make sliding electrical engagement with toggle member 85 on a contact portion of lug 98, indicated by numeral 101.

Slidable rod 84 forms one element of an auxiliary switch mechanism, the function whereof is to short-circuit the incoming line to a suitable return path, such as ground, through an auxiliary terminal. Such a terminal is provided by an angular bracket 102 secured in fixed relation to housing 76 by the use of a threaded stud 103 cemented therein and a nut 104. Contact 102 is of sufficient length to permit engagement therewith of slidable rod 84. Slidable rod 84 is provided on the upper portion thereof with a fixed collar 84' arranged to be engaged by the upper extremity of a helical spring 105, the lower extremity of which engages lip 90 of insulating sleeve 89. The function of spring 105 is to force rod 84 into engagement with contact 102. Bracket 86 and sleeve 89 are provided with a hole 106 arranged to engage a latch element 107 forming a part of toggle member 85. A reduced portion 108 is provided in rod 84 and is arranged to engage the extremity 109 of latch 107.

A biasing spring 110 is attached by a screw 111 to toggle member 85 and by hooking or otherwise to a projecting portion 112 of bracket 86. Biasing spring 110 exerts a force between toggle 85 and bracket 86, tending to rotate the assembly of elements mounted in fixed relation with respect to bracket 86 and support 82 in a counterclockwise direction with respect to toggle 85 about pivot point 93. Such rotation is restricted by engagement of latch 107 with reduced portion 108 of rod 84. A latch 113, pivotally mounted by a pin 114 in frame 91, is provided to engage the outer extremity or armature portion of toggle member 85 in the vicinity of electromagnet 83. Latch 113 is provided with a hook-shaped end 115 arranged to engage a notched-out portion 116 of toggle member 85. A biasing spring 117 is provided between frame 91 and latch 113, tending to rotate the latter in a counterclockwise direction about pin 114.

There are two principal conducting paths through device 75. One end of winding 92 is made electrically common with bracket 86 and frame 91 by the use of a screw 118. The other end of winding 92 is connected to toggle member 85 and to a flexible lead 121 by the use of a screw 119 and nut 120. Lead 121 is connected to the lower extremity of rod 84 by a screw 122. The normal conducting path through device 75 is from the incoming terminal formed by catch 97 through latch 96, bracket 86, winding 92, and toggle member 85 to the outgoing terminal formed by lug 98. The short-circuiting path through device 75 is from incoming terminal 97 through latch 96, bracket 86 and winding 92 to toggle member

85 and thence through flexible lead 121 and slidable rod 84 to the auxiliary terminal formed by contact 102.

The electrical relationship of the principal elements forming the conducting paths through device 75 is shown schematically in Fig. 5, in which device 75 is shown within a closed broken line. In Fig. 5, the main conducting path through device 75 is shown between terminals 97 and 98 and the short-circuiting path between terminals 97 and 102. It will be noted that in both cases the entire line current flows through winding 92 of electromagnet 83.

In considering the operation of device 75, it is assumed that device 75 is connected in a line of an electrical distribution circuit in combination with a reclosing circuit interrupter, as in the case of the first embodiment described. The incoming line is connected to terminal 97, the outgoing or load line is connected to terminal 98, and terminal 102 is connected to suitable return path, such as ground.

For normal operation, cutout device 75 is as represented in Fig. 4. Door assembly 79 is maintained in its closed position by latching engagement between latch 96 and catch 97. Slidable rod 84 is maintained in its latched position by engagement of latch 107 with reduced portion 108. In other words, the main switching mechanism of cutout 75 formed by latch 96 and catch 97 is closed, thereby completing the conducting path from terminal 97 to terminal 98. The auxiliary switch mechanism formed by slidable rod 84 and bracket 102 is in an open position and, accordingly, the conducting path between terminals 97 and 102 through device 75 is incomplete. The biasing action of spring 110 serves to maintain latch 107 in engagement with reduced portion 108. Latch 113 is engaged with notched-out portion 116 of toggle member 85 and is prevented from being biased away from notch 116 by interference therewith.

If a fault condition occurs in the load line leading from terminal 98 of cutout 75, the current flowing through the normal conducting path thereof and particularly through winding 92 is substantially increased in magnitude. When a predetermined magnitude is reached, as determined by the magnetic air gap between frame 91 and the armature portion of toggle member 85, and the biasing force of spring 110, the magnetic force exerted on toggle member 85 causes rotation thereof in a counterclockwise direction. Such rotation continues until the armature portion of toggle member 85 is in touching engagement with frame 91.

The length of latch 107 is such that upon rotation of toggle member 85, latch 107 is disengaged from reduced portion 108 of rod 84. Rod 84 is thereby released from its latched position and is biased by action of spring 105 into touching engagement with bracket 102, as indicated in Fig. 4 by a broken-line view of rod 84. As toggle member 85 is rotated by magnetic action, latch 113 is freed from engagement with notch 116 and is biased into its unlatched position, indicated in Fig. 4 by a broken-line view of latch 113. In this position, latch 113 no longer engages toggle member 85.

Upon engagement of rod 84 with bracket 102, the short-circuiting path through cutout 75 is completed, thereby imposing a relatively low-impedance short-circuit between terminals 97 and 102 or between the incoming line and ground. Such a short-circuit tends further to increase the

current in the incoming line over its previous value and causes opening of an associated circuit interrupting device, such as an automatic reclosing circuit breaker (not shown).

Opening of an associated circuit interrupting device causes the current through cutout 75, and particularly through winding 92 to be reduced to zero. Accordingly, magnetic force ceases to be exerted by magnet 83 on toggle member 85. Toggle member 85, thus, is permitted to drop sufficiently to cause unlatching to occur between latch 96 and catch 97. When such unlatching action occurs, door assembly 79 is no longer latched in its closed position and is permitted to drop open around pivot 80 to a position shown in Fig. 4 by a partial broken-line view of door 79. When door 79 drops open, both the main and auxiliary switch elements of cutout 75 are opened thereby interrupting the main and short-circuiting conducting paths through device 75. The faulted load line, which is connected to terminal 98 is isolated from ground following opening of door 79, as in the case of the first embodiment described.

Following clearing of the fault condition in the load line device 75 may be reset or again placed in condition for normal operation by an operator. Such resetting includes returning rod 84 and toggle member 85 to their latched positions, as shown in Fig. 4, and then returning door assembly 79 to its closed position by pivoting it about hinge pin 80 and effecting latching engagement between latch 96 and catch 97. The latter step also effects closing of the main conducting path through device 75. A conventional eyelet 123 may be provided in door support 78 to aid in closing door assembly 79 by the use of an operating stick.

It will be noted that in the second embodiment of my invention herein described a fuseless cutout is provided wherein only a single current-responsive element is employed. Such an element is made to cause a metallic short-circuit to be imposed on a distribution circuit in response to a fault condition therein and subsequently to cause opening of the cutout and isolation of the faulted line from ground, in response to current ceasing to flow through the cutout and particularly the magnetic winding, such as would be caused by interruption of the short-circuit current by an associated circuit interrupting device.

By the use of a cutout device constructed in accordance with my invention, a metallic short-circuit is imposed on a distribution circuit in response to a fault condition therein without accompanying arcing conditions at the cutout device. By providing a short-circuit at a cutout device to force operation of an associated circuit interrupting device, a relatively low predetermined current may be employed to cause operation of the cutout device, thereby providing a relatively higher degree of protection that would otherwise be the case.

While I have shown and described certain preferred embodiments of my invention, it will be understood that my invention may well take other forms and I, therefore, aim in the appended claims to cover all such changes and modifications as fall within the true spirit and scope of my invention.

What I claim as new and desire to secure by Letters Patent of the United States is:

1. An electrical protective device for use in connecting apparatus to be protected and supplied with current to a line leading from a circuit interrupter responsive to the flow of ab-

normal current in said line, comprising main switching means connected in series with said line and arranged to be closed in normal operation of said device, auxiliary switching means comprising a stationary contact electrically connected to an auxiliary return path for said current and a movable contact electrically connected to said line and engageable with said stationary contact, said contacts being unengaged in normal operation of said device, means responsive to a predetermined current flowing through said main switching means to cause engagement of said movable contact with said stationary contact and interconnection of said line and said return path to cause abnormal current to flow in said line, a magnetic winding connected electrically in series with said line and an armature for said winding, said armature being responsive to flow of said abnormal current to maintain said auxiliary switching means in said contact engaging position and thereafter to open said main and disengage said auxiliary switching means in response to subsequent interruption of said abnormal current.

2. An electrical protective device for use in connecting apparatus to be protected and supplied with current to a line leading from a circuit interrupter responsive to the flow of abnormal current in said line, comprising main switching means connected in series with said line and arranged to be closed in normal operation of said device, auxiliary switching means comprising a stationary contact electrically connected to an auxiliary return path for said current and a movable contact electrically connected to said line and engageable with said stationary contact, said contacts being unengaged in normal operation of said device, means including a thermostatic element responsive to a predetermined current flowing through said main switching means to cause engagement of said movable contact with said stationary contact and interconnection of said line and said return path to cause abnormal current to flow in said line, a latch movable to a holding position to maintain said auxiliary switching means in said contact engaging position and movable to a released position to permit disengagement of said auxiliary switching means, a magnetic winding connected electrically in series with said line and an armature for said winding engageable with said latch in response to flow of said abnormal current to maintain said latch in said holding position and said auxiliary switching means in said contact engaging position, said armature being responsive to subsequent interruption of said abnormal current to permit release of said latch and effect opening of said main and disengagement of said auxiliary switching means.

3. An electrical protective device for use in connecting apparatus to be protected and supplied with current to a line leading from a circuit interrupter responsive to the flow of abnormal current in said line, comprising main switching means connected in series with said line and arranged to be closed in normal operation of said device, auxiliary switching means comprising a stationary contact electrically connected to an auxiliary return path for said current and a movable contact electrically connected to said line and engageable with said stationary contact, said contacts being unengaged in normal operation of said device, and current responsive means including a magnetic winding

and an armature therefor responsive to a predetermined current flowing therethrough to effect engagement of said movable contact with said stationary contact and interconnection of said line and said return path to cause abnormal current to flow in said line, said armature being responsive to said abnormal current to maintain said auxiliary switching means in said contact engaging position and responsive to subsequent interruption of said abnormal current to there- 10 after cause opening of said main and disengagement of said auxiliary switching means.
